(57) **CLAIM**

The ornamental design for a shoe as shown and described.

DESCRIPTION

FIG. 1 is a front, right, and top perspective view of a shoe showing my new design;

FIG. 2 is a rear, left, and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of an area labeled "9" in FIG. 1; and,

FIG. 10 is a partial enlarged view of an area labeled "10" in FIG. 2.

The shoe for the left foot is a mirror image of the shoe for the right foot as shown in FIGS. 1 to 8, which is not shown but is also claimed.

In addition, the dot-dash broken lines in FIGS. 1, 2, 9, and 10 depict the boundaries of the enlargements that form no part of the claimed design.
